UNITED STATES PATENT OFFICE.

SAMUEL P. GEHRET, OF YORK, PENNSYLVANIA.

DOOR-LOCK.

1,304,175.

Specification of Letters Patent. Patented May 20, 1919.

Application filed June 24, 1918. Serial No. 241,572.

To all whom it may concern:

Be it known that I, SAMUEL P. GEHRET, a citizen of the United States, residing at York, in the county of York and State of Pennsylvania, have invented certain new and useful Improvements in Door-Locks, of which the following is a specification, reference being had to the accompanying drawings.

10 This invention relates to an improved door lock, and has for its primary object to provide a locking device particularly designed for application to the doors of commercial vehicle bodies whereby the doors 15 may be easily and quickly opened, while at the same time access to the interior of the vehicle body by unauthorized persons may be effectually prevented.

It is another important object of the invention to provide a locking device for the above purpose which is so constructed that the doors are locked both on the interior and the exterior thereof.

And it is a further general object of my 25 invention to provide a door locking device the various elements of which are of simple and durable construction, effective and reliable in their operation and capable of being manufactured at relatively small cost.

30 With the above and other objects in view the invention consists in the improved combination, construction and relative arrangement of the several parts as will be herein-after more fully described, subsequently 35 claimed and illustrated in the accompanying drawing in which similar reference characters designate the corresponding parts throughout the several views; and wherein:

Figure 1 is an exterior elevation showing 40 my improved locking device in its applied position, portions of the doors being broken away;

Fig. 2 is a sectional view taken on the line 2—2 of Fig. 1;

45 Fig. 3 is a section taken on the line 3—3 of Fig. 1;

Fig. 4 is an end elevation of the operating lever and the keeper therefor, showing the lever locked.

50 Fig. 5 is a section taken on the line 5—5 of Fig. 2; and

Fig. 6 is a section taken on the line 6—6 of Fig. 1.

Referring in detail to the drawing, D and 55 D' indicate the two doors of the motor vehicle body, said doors at their outer verti-

cal edges being pivotally or hingedly mounted upon the side walls of the vehicle body in any approved manner for outward swinging movement. A balance strip S secured 60 to the outer face of the door D projects laterally from the free vertical edge thereof for lapping engagement upon the outer face of the other door D' as shown in Fig. 2, whereby when the door D which is equipped 65 with the locking mechanism to be herein-after described is locked in its closed position, the door D' will likewise be held closed against outward swinging movement.

In the accompanying drawing wherein I 70 have illustrated one preferred embodiment of my invention, 5 designates a rod or shaft which is rotatably mounted in a transverse opening d in the door D adjacent the free vertical edge thereof. The shaft 5 has a 75 circular head 6 formed upon one of its ends while the other end of said shaft is reduced in diameter as at 7 and formed with a threaded terminal 8. A metal bar 9 is provided with an opening in one of its ends to 80 receive the shaft 5, said bar when the device is applied being interposed between the head 6 on said shaft and the face of the door D. This bar extends horizontally upon one side of the head 6 and is rigidly secured to the 85 door by means of suitable screws shown at 10. The bar 9 is formed upon its rear face with a boss 11 surrounding the opening in the end of said bar through which the shaft 5 is engaged. A pin 12 is inserted through 90 a transverse opening in the shaft 5 and the projecting ends of this pin engage the boss 11 whereby the shaft is held against axial shifting movement through the bar 9. The boss 11 and the pin 12 are disposed in a 95 countersink or recess 13 in the face of the door. At its other end the bar 9 terminates in a reversely curved hook 14 the bill or terminal of which is disposed in parallel relation to the body of the bar.

To the head 6 an operating bar or lever 15 is securely riveted as at 16. This lever is formed of spring steel and preferably tapers in width at one of its ends as shown in Fig. 1, said end of the bar being provided 105 with a knob or handle 17 having a bifurcated shank 18.

The end portion of the resilient bar or lever 15 which projects in the opposite direction from the head 6, and which is relatively short, has a transversely curved terminal 20. When the bar or lever is m

to a horizontal position, the longitudinal edges of this curved terminal are adapted for engagement with the body of the bar 9 while the convex surface of said terminal has bearing engagement against the inner face of the bill of the hook 14. By thus transversely curving the terminal of the lever, it may more readily enter the hook 14 and by its resilient bearing engagement at the outer edges and the medial portion thereof with the terminal hook of the bar 9, the lever is more effectively held against vibration or relative movement whereby rattling and the noise incident thereto is obviated.

15 The reduced inner end portion 7 of the shaft 5 is of rectangular or other polygonal shape in cross section and upon the same a plate 21 is engaged, said plate having a boss 22 projecting from one face thereof which 20 will allow for varying thickness of doors by reversing said plate and against the end of which a retaining nut 23 threaded on the terminal 8 of the shaft is adapted to engage, said nut holding the plate 21 against the 25 shoulder 7' at the inner end of the reduced portion 7 of the shaft which is disposed in spaced relation to the inner face of the door. The ends of the plate 21 projecting in opposite directions from the central boss 30 22 provide arms in which the bolts 24 are engaged. 25 designates the locking rods which are flattened at one of their ends and provided with openings therein to receive the bolts 24. Nuts 26 are threaded upon the 35 bolts 24 to retain the locking rods in connection with said bolts. The rods 25 extend vertically and are loosely movable through the openings 29 provided in the angular ends 28 of the guide members 27 which are 40 fixed to the inner face of the door at its upper and lower edges. These rods are adapted for engagement in suitable sockets or keepers indicated at 30.

I have also provided means whereby the 45 actuation of the bar or lever 15 by unauthorized persons may be prevented and the doors locked exteriorly thereof as well as upon the interior. This means as herein shown consists in a keeper generally indicated by 50 the numeral 31, said keeper being in the form of an elongated U-shaped plate, one arm 32 of which is adapted to be secured to the outer face of the door D'. The other arm of this keeper plate, designated 33, is 55 vertically disposed and has a slot 34 therein opening upon the upper edge of said arm. At each side of this slot, the upper edge of the arm is inwardly turned or bent to provide angularly disposed lips 35. When the 60 lever 15 is moved to its locking position, the bifurcated shank 18 of the handle or knob 17 moves downwardly into the slot 34, the end of the lever being sprung inwardly toward the face of the door so that the lever bar will move downwardly between the lips 65

35 and the arm 32 of the keeper. When the inward pressure on the lever bar is released, said bar will spring outwardly, owing to its inherent resiliency, against the inner side of the keeper arm 33 and beneath the inwardly 70 projecting lips 35 on the upper end of said arm. The hasp of a padlock may be now engaged through the bifurcation of the shank 17 as indicated in Fig. 1 to securely lock the bar 15 to the keeper. In this manner, the operating lever for the locking bolts 75 25 may be securely locked against operation so that the doors cannot be opened by unauthorized persons. As the other end of the lever is operatively engaged in the hook 14 on the end of the bar 9 in the manner above explained, it will be seen that the resilient lever bar will not vibrate or rattle against the other associated parts of the locking device and the objectionable noises which 80 85 would be incident to such rattling of the parts are thus obviated.

When it is desired to open the doors it is only necessary to remove the padlock and then force the end of the lever bar 14 inwardly and then upwardly out of engagement with the keeper 31. In this upward movement of the lever, the shaft 5 is rotated and through the medium of the plate 21 on the inner end of said shaft, the locking bolts 90 25 are vertically moved in relatively opposite directions and disengaged from the keepers 30. The doors D and D' can then be swung outwardly to their open positions.

From the foregoing description taken in 100 connection with the accompanying drawing, the construction, manner of operation and several advantages of my improved locking device will be clearly and fully understood. While the invention is primarily designed 105 with a view to providing a simple and effective locking means for the doors of commercial vehicle bodies, it is of course manifest that the device can also be advantageously employed for various other analogous purposes. The parts of the improved door lock can be readily assembled and applied in operative position, without necessitating any material alterations in the doors of the vehicle body construction. A device 110 constructed and operating in the manner described provides easily and quickly operable means for securely locking the doors in closed position upon both the interior and exterior thereof. As no springs or other 115 easily breakable elements are employed, the device is not liable to get out of order, but on the contrary, the various parts being of simple form, the invention as a whole will be highly durable and serviceable in practical use.

While I have herein shown and described the preferred construction and relative arrangement of the several elements, it is to be understood that the device is susceptible 120 125 130

of considerable modification therein, and I therefore reserve the privilege of adopting all such legitimate changes as may be fairly embodied within the spirit and scope of the 5 invention as claimed.

Having thus described my invention, what I claim is:—

1. In a locking device for doors, an operating lever, a rod fixed to said lever intermediate of its ends and rotatably mounted in the door, an arm fixed to said rod, locking bolts operatively connected to the ends of said arm, a plate engaged upon the rod and secured to the door, said plate having a hook formed on one end within which one end of the operating lever is adapted to frictionally engage when the lever is moved to dispose the bolts in locking position, and a keeper member to receive the other end of 20 said operating lever.

2. In a locking device for doors, a resilient operating lever, a rod fixed at one of its ends to said lever and rotatably mounted in the door, locking bolts operatively connected 25 to the other end of said rod, a plate engaged at one of its ends upon the rod and fixed to the door, said plate having a hook formed on its other end and one end of said operating lever being transversely curved to enter the hook and frictionally coat with said plate to hold the lever against vibration when moved to dispose the bolts in their locking 30 positions.

3. In a locking device for doors, a horizontally disposed plate fixed in the door, a rod rotatably mounted in one end of said plate and extending through the door, locking means operatively connected to the in- 35

ner end of said rod, a resilient operating lever fixed intermediate of its ends to the 40 outer end of said rod, one end of said lever being transversely bowed or curved, and said plate being provided with means on its other end with which the bowed end of the lever is adapted to coact when said lever is actuated to dispose the locking means in its effective locking position and thereby effect the resilient frictional engagement of the 45 end of the lever upon said plate whereby the lever is held against vibration. 50

4. In a locking device for doors, a resilient lever bar pivotally mounted upon the door intermediate of its ends, a plate fixed to the door and having a terminal hook with which one end of the lever bar is adapted to 55 frictionally coact when said bar is moved to its locking position, an operating handle having a shank fixed to the other end of the lever bar, and a keeper provided with spaced arms, one of said arms being slotted to receive the shank of said handle and having angularly disposed terminal lips at opposite sides of said slot, said lever when moved to its locking position being sprung from its normal plane and engaged between the arms 60 of the keeper whereby upon the release of the lever handle, said lever will frictionally coact with the slotted arm of the keeper beneath the terminal lips thereon.

In testimony whereof I hereunto affix my 70 signature in the presence of two witnesses.

SAMUEL P. GEHRET.
